CHALK HOLDER

Wilfrid H. Des Jardins, Haverhill, Mass.

Application September 10, 1938, Serial No. 229,352

1 Claim. (Cl. 273—20)

The present invention relates to new and useful improvements in chalk holders particularly for cue chalk and has for its primary object to provide, in a manner as hereinafter set forth, a device of this character embodying a novel construction, combination and arrangement of parts through the medium of which a cue chalk may be suspended in any convenient location so that the same may be easily handled by the user, and

10 when not in use will be held conveniently and out of the way of the player of a game of billiards or pool.

Other objects of the invention are to provide a chalk holder of the aforementioned character which will be comparatively simple in construction, strong, durable, highly efficient and reliable in use, compact, light in weight, and which may be manufactured at low cost.

All of the foregoing and still further objects 20 and advantages of the invention will become apparent from a study of the following specification, taken in connection with the accompanying drawing wherein like characters of reference designate corresponding parts throughout the 25 several views, and wherein:

Figure 1 is a vertical transverse sectional view of my invention.

Figure 2 is a side elevational view of the invention.

30 Figure 3 is a perspective view of the spring tube.

Figure 4 is a bottom plan view of the chalk clamp.

Referring now to the drawing in detail, it will 35 be seen that the reference numeral 5 designates a length of tubing, constructed of metal or other suitable material, having screw threads 6 and 7 at its top and bottom end portions.

An internally threaded cap 8 is screwed onto 40 the threaded top end portion of the tube 5 and is provided with an integral eye 9 on its top side from which the device is suspended. On the under side of the cap 8 and within the same there is provided an eye 10 from which is suspended a 45 tension spring 11. An internally threaded collar 12 is screwed onto the bottom end of the tube 5, and protects the same from damage.

The tension spring 11 is releasably secured at 50 its upper end to the eye 10 while its lower end is releasably secured to the spring tube 13 and acts to retract the spring tube 13 when the same is extended from the tube 5 when the device is in use.

The top end portion of the spring tube 13 is

open as at 14 to permit the same to come to rest against the cap 8 and thus avoid damage to the eye 10 when tension on the spring 11 is relieved suddenly. An eye 15 is provided on the inner bottom end portion of the spring tube 13 to which the tension spring 11 is secured, while an eye 16 is provided on the bottom end to which one end of a length of chain 17 is suspended.

A chalk clamp 18 having clamping jaws 19 is secured to the other end of the chain 17 through 10 the medium of an eye 20 which has a shank 21 extending therefrom which extends through the clamp 18 and is riveted thereto as shown at 22.

A conventional cue chalk 23 is frictionally held 15 between the jaws 19 and may be easily removed when desired.

The operation of the device is thought to be manifest but may be briefly described as follows:

The device is suspended from a convenient support through the medium of the eye 9 with the 20 chalk clamp 18 at such a level as to be conveniently within the reach of the pool player when chalking of the cue tip is desired. When chalking a cue the chalk clamp 18 and chalk 23 are pulled to a lower level thus exerting a tension on 25 the tension spring 11 which tension when released permits the spring 11 to withdraw the chalk 23 to a higher level and clear of the user's head.

Although I have shown and described herein 30 a preferred embodiment of my invention, it is to be definitely understood that any change or changes may be made in the structure and arrangement of the parts of the invention as claimed.

What is claimed is:

A chalk holder of the class described comprising 35 an elongated tube, a cap threaded to the upper end thereof, an upwardly extending suspension eye on the cap, a downwardly extending 40 suspension eye carried by the cap and located within the tube, a coiled spring having one end connected with the last-mentioned eye, a small tube encircling the spring and having its upper end open to fit over the second mentioned eye 45 and the lower end of the small tube being closed and having an upwardly extending member thereon for receiving the lower end of the spring, a chain connected with the lower end of the small tube and passing through the lower end of the 50 first-mentioned tube and a chalk holder connected with the lower end of the chain.
